A. & P. P. MEREDITH.

Hand Loom.

No. 71,035.

Patented Nov. 19, 1867.

United States Patent Office.

A. MEREDITH AND P. P. MEREDITH, OF MAXINTUCKEE, INDIANA.

Letters Patent No. 71,035, dated November 19, 1867.

IMPROVEMENT IN HAND-LOOMS.

The Schedule referred to in these Letters Patent and making part of the same.

TO ALL WHOM IT MAY CONCERN:

Be it known that we, A. MEREDITH and P. P. MEREDITH, of Maxintuckee, in the county of Marshall, and State of Indiana, have invented a new and useful Improvement in Hand-Looms; and we do hereby declare that the following is a full, clear, and exact description thereof, which will enable others skilled in the art to make and use the same, reference being had to the accompanying drawings, forming part of this specification, in which—

Figure 1 is a vertical longitudinal section of a loom, taken in the line $z z$, fig. 2, showing our improved arrangements for throwing the shuttle and working the treadles by the motion of the lay.

Figure 2 is a top view of the same.

Figure 3 is a detached top view of the shuttle-thrower.

Figure 4 is a detached front view of the same.

Similar letters of reference indicate corresponding parts.

This invention relates to improvements in the construction and arrangement of a hand-loom, and consists in a device connected with the shuttle-driver in such a manner that the motion of the lay shall operate on the drivers to throw the shuttle, and also a device connecting the treadle-shaft with the lay to work the heddles. By the application of these devices the operation of a hand-loom is rendered easy and effective.

A A represent the frame of an ordinary hand-loom, B the warp-beam, C the cloth-beam, D the lay, E the breast-beam, F the heddles, G the treadles, and H the treadle-cam shaft. A semicircular cam-plate, I, is pivoted centrally to a cross-beam, J, on the lay-frame, to operate as a shuttle-thrower by the moving of the lay. At the centre of the plate I is a cam-point, a , projecting above the plate, and pointing towards the treadles. On a cross-beam, K, behind the treadles, a dog, b , is pivoted at one of its ends, the other end of the dog being three-pronged, like a trident, with the middle prong c projecting beyond the side prongs $c' c'$. The dog b lies between two spring-bars $e e$ which hold it in place centrally, and in line with the cam-point a on the cam-plate I, by means of the spiral springs $g g$, when it is not drawn aside by the shuttle-thrower, as hereinafter described. At the sides of the cam-plate I, two levers, $h h$, are pivoted near their centres on rods $k k$ to the cross-beam J, which rods $k k$ bend over to the front side of the lay, and are connected by rods $l l$ with the shuttle-drivers L L, to which they give motion for throwing the shuttle. The outer ends of the levers $h h$ are connected with springs $m m$, placed at the front side of the lay on the cross-beam J, by which springs the levers $h h$ are suddenly reversed in their position, to operate the drivers L L, as hereinafter described. When the lay D is moved forward, then the middle prong c of the dog b passes on either side of the cam-point a , and strikes against the inner end of one of the levers h , and pushes it back on the cam-plate I until a little projection or latch, s , on the end, catches upon a shoulder, t , at the back part of the cam-plate I, as shown clearly in detached views, figs. 4, 5. When the lever h is thus pushed back at its inner end, the outer end draws the spring m connected with it, while at the same time, by means of the bent rod k and the connecting-rod l , the driver L secured to it is thrown out to the end of the box ready to strike the shuttle. The lever is held in this position by latch s and shoulder t , and with the spring m contracted, until there is another movement of the lay. When the lever h is thus pushed back by the dog b , one of the short prongs c' comes up against a guard-block, a' , on one side of the cam-point a , and gives a little turn to the cam-plate I, so as to throw the cam-point a out of line with the point of the prong c on the dog b , and also at the same time set the latch s on the shoulder t , as just described. By the next movement forward of the lay D, the prong c' will pass on the opposite side of the cam-point a and push the other lever h back, as before described, till it catches by the latch s , when at the same moment, by the reverse action of the cam-plate I, produced by the prong c' coming in contact with the guard-block a' on that side of the cam-plate, the latch s on the lever h , previously operated upon, will be released from the shoulder t , and the spring m will instantly reverse the position of the lever and throw forward the shuttle-driver L, with which it is connected. Thus the two levers will operate alternately to move the drivers L L back and forth, and throw the shuttle with every movement to and fro of the lay, and with the utmost certainty in their execution. On the treadle-cam shaft H, at the middle, is a wheel, M, provided with four catch-bars $n n$, which catch one end of a pawl, p , that is attached at its other end to the under side of the cross-beam J on the lay-frame,

so that when the lay is drawn back to strike up the weft, the cams or tappets *q q*, on either end of the shaft *H*, shall strike the treadles *G* that are made fast to the heddle-bars *v v*, to move them both up and down to shed the warp as required. At the sides of the loom are placed vertical heddle or sash-guides *N*, that are grooved to receive the ends of the heddle-rods *w w*, which work in them. The rods *w w* are set upon standards, and are supported on spiral springs, which relieve any undue strain on the warp in shedding.

Having thus described our invention, what we claim as new, and desire to secure by Letters Patent, is—

The cam-plate *I*, in combination with the three-pronged dog *b*, the levers *h h*, the springs *m m*, and the shuttle-drivers *L L*, constructed, arranged, and operating substantially in the manner and for the purpose herein shown and described.

A. MEREDITH,
P. P. MEREDITH.
